UNITED STATES PATENT OFFICE.

ISAAC F. WILLIAMS, OF BRISTOL, ASSIGNOR TO THE NATIONAL RUBBER COMPANY, OF PROVIDENCE, RHODE ISLAND.

DESIGN FOR RUBBER OVERSHOES.

Specification forming part of Design No. 5,094 dated July 4, 1871.

To all whom it may concern:

Be it known that I, ISAAC F. WILLIAMS, of the city of Bristol, in the county of Bristol and State of Rhode Island, have originated a new and artistic Design for the Ornamentation of Rubber Overshoes; and I do hereby declare that the following specification, taken in connection with the drawing furnished and forming a part of the same, is a clear, true, and exact description thereof.

Figure 1 represents, in perspective, a rubber overshoe manufactured after my design. Fig. 2 represents the same in top view.

A is a raised surface, made up of a series of beaded ribs extending across the vamp to a point adjacent to the soles on each side, and occupying

a space lengthwise, extending from near the upper portion of the vamp to near the toe. The balance of the shoe is provided with a smooth surface. The raised ribbed surface on the vamp adds greatly to the beauty and finish of the shoe.

Having thus described my design, I claim as new—

The above-described design for the ornamentation of rubber shoes, as shown.

ISAAC F. WILLIAMS.
